(57) **CLAIM**

The ornamental design for tactical pants, as shown and described.

DESCRIPTION

FIG. 1 is a perspective view of tactical pants;

FIG. 2 is a front view of the tactical pants of FIG. 1;

FIG. 3 is a rear view of the tactical pants of FIG. 1;

FIG. 4 is a right side view of the tactical pants of FIG. 1;

FIG. 5 is top view of the tactical pants of FIG. 1;

FIG. 6 is a bottom view of the tactical pants of FIG. 1;

FIG. 7 is a close-up front view of the buckle of the tactical pants of FIG. 1, shown unbuckled;

FIG. 8 is a perspective view of the tactical pants, showing the second embodiment;

FIG. 9 is a rear perspective view of the tactical pants of FIG. 8;

FIG. 10 is a front view of the tactical pants of FIG. 8;

FIG. 11 is a rear view of the tactical pants of FIG. 8;

FIG. 12 is a right side view of the tactical pants of FIG. 8;

FIG. 13 is a top view of the tactical pants of FIG. 8;

FIG. 14 is a bottom view of the tactical pants of FIG. 8; and, FIG. 15 is a close-up front view of the tri-glide slide of the tactical pants of FIG. 8.

The broken lines shown in FIG. 1 of the snap button and FIG. 8 of the snap button and buckle are included for the purpose of illustrating environmental structure and form no part of the claimed design. All other broken lines represent stitching.

1 Claim, 8 Drawing Sheets
